SHEET REGISTERING MECHANISM FOR
PRINTING MACHINES

William K. Eckhard, Newark, N. J., and Edwin W. Goodwin, New Rochelle, N. Y., assignors to R. Hoe & Co., Inc., New York, N. Y., a corporation of New York

Application November 17, 1942, Serial No. 465,898

10 Claims. (Cl. 271—59)

1

This invention relates to sheet registering devices for printing machines, and more particularly to improved sheet-guiding method and mechanism for "side guiding" sheets of relatively soft material, such as thin metal or cardboard.

In machines of this class, side guides are provided which engage the edges of the sheet as it is forwarded to the printing cylinders to thereby guide the sheet so that it will be printed in proper register. Sometimes there is a variation in the width of the sheets which are, however, of the same nominal dimensions, therefore it is customary to arrange one of the guides so that it forms a positive positioning means, while the other guide is yieldingly supported and biased so that it bears against an edge of the sheet with a yielding pressure. Thus, even though the dimensions of the sheet vary to some extent, the printing is registered to the side that is engaged by the rigid guide.

Such guides will operate satisfactorily when the side edges of the sheet are perfectly straight and are square with the front edge, but if they are not straight and square, they may not pass the guides freely and the resulting interference may effect the register of the printing.

Registering devices have been provided to overcome this difficulty, and such device is disclosed in U. S. Patent No. 1,780,348, granted November 4, 1930, to William K. Eckhard. The Eckhard patent discloses sheet-registering mechanism which incorporates side guides arranged so that they properly position the sheet for side register and then recede so that there is no interference with the sheet as it moves past the side guides. This mechanism has proven highly satisfactory when handling metal sheets of normal gauge, but when relatively thin metal sheets, or cardboard sheets are employed, the side guides tend to curl or turn the edges of the sheets.

It is, therefore, an object of this invention to provide improved side registering method and mechanism for printing machines that are employed for printing on relatively thin or relatively soft material, and which will accurately position the sheet with reference to the printing cylinders without injuring the edges of the sheet and which can be used with sheets that are not entirely accurate as to shape or dimensions.

Another object of this invention is to provide an improved sheet-guiding mechanism for side guiding sheets formed of relatively thin or relatively soft material, the guiding mechanism including a non-yieldable stop and an opposed highly sensitive yieldable stop which freely moves

2

to accurately conform to the width of a sheet without curling or otherwise injuring the edge of the sheet.

A further object of this invention is to provide an improved sheet-guiding method and mechanism for side guiding sheets formed of relatively thin or relatively soft material, the guiding mechanism being so constructed and arranged that all side guiding instrumentalities which engage the sheet are rotatably mounted so that their effective guiding surfaces move in the direction of movement of the sheet.

It is also an object of this invention to provide a sheet-guiding mechanism of generally improved construction and arrangement, whereby the device will be simple, durable, and inexpensive in construction, as well as convenient, practical, serviceable, and efficient in its use.

With the foregoing and other objects in view 20 which will appear as the description proceeds, the invention resides in the combination and arrangement of parts, and in the details of construction hereafter described and claimed, it being understood that various changes in form, proportion and minor details of construction may be made within the scope of the claims without departing from the spirit or sacrificing any advantages of the invention.

For a complete disclosure of the invention, a 30 detailed description thereof will now be given in connection with the accompanying drawings forming a part of the specification, wherein:

Figure 1 is a vertical transverse sectional view, taken through a printing machine having the 35 improved sheet-guiding mechanism applied thereto, the sheet-guiding mechanism being shown in elevation;

Figure 2 is a vertical sectional view, taken through the fixed sheet-guide roller and its supporting mechanism, parts appearing in elevation;

Figure 3 is a vertical sectional view, taken through the yieldable sheet-guide roller and its supports, parts appearing in elevation;

Figure 4 is a plan view of the mechanism depicted in Figure 3, the view being seen in the direction indicated by the arrow 4 in Figure 3;

Figure 5 is an end elevation of the mechanism shown in Figure 3, the view being seen in the 50 direction indicated by the arrow 5 in Figure 3;

Figure 6 is a similar view of the opposed end of the structure shown in Figure 3, the view being seen in the direction indicated by the arrows 6 in Figure 3;

Figure 7 is a side elevation of the mechanism;

shown in Figure 3, and depicting its components in a different operative position;

Figure 8 is a horizontal sectional view, taken approximately on the line 8—8 of Figure 3;

Figure 9 is a diagrammatic view depicting the relative effective circumferences presented to an edge of a passing sheet by a guide roller of given diameter, which is rotatable about a vertical axis, and a guide roller of the same diameter, which is rotatable about an inclined axis;

Figure 10 is a side elevation of a modified sheet-guide roller; and

Figure 11 is a similar view of further modification.

Referring to the drawings, in which similar reference characters designate corresponding parts, there is depicted side frames 12 and 12a of a printing machine and a cross bar 13 on which supports 14 and 15 are slidably mounted. Side guide rails 16 and 17 are secured to these supports by means of screws 18 and 19, and a suitable sheet supporting member 20 is located so that its upper surface is in horizontal alignment with the upper surfaces of the side guide rails 16 and 17, for a purpose to be hereinafter disclosed.

A supporting block 21 is secured to the side guide rail 17 by screws 22, and this block (Fig. 2) is provided with an inclined cylindrical aperture 23 for the reception of a shaft 25 which is secured to the block 21 by a pin 26, or other suitable securing device. The shaft 25 is provided with a collar 27, which engages the block 21, and anti-friction bearing units 28 and 30 are supported by the shaft 25 between the collar 27 and a securing nut 31, the bearing units being held in spaced relation, by a conventional spacing ring 32. The outer rings of the bearing units 28 and 30 are received within axially-aligned recesses 33 and 35, formed in a sheet-guide roller 36. By this arrangement, the roller is supported for rotation about an inclined axis for a purpose to be hereinafter explained. The peripheral surface 37 of the roller 36 is longitudinally curved, so that it presents rotatable circular sheet-guiding surfaces of varying radii, as best seen in Figure 2. This roller is provided with an annular flange 38 having a conical surface 40 which is disposed to engage a side edge of a sheet that is supported on the members 20 and the sheet-guide rail 17, and the portion of the surface 40 which engages the side edge of the sheet is disposed in substantially perpendicular relation to the supported sheet, for a purpose to be more fully explained hereinafter.

A roller-supporting bracket 41 (Figures 1 and 3) is carried by the sheet-guide rail 16, and the foot of the bracket 41 is secured to the rail 16 by means of screws 42, as best seen in Figure 3. This bracket has an overhanging portion or extension, that is provided with an aperture 43, for the reception of a pin or shaft 45, which pivotally supports a composite link 46 that has a body portion 47. The upper terminal of the link 46 is bifurcated, as best seen in Figures 3, 4, and 6, and the resulting furcations 48 are disposed at each side of the overhanging portion of the bracket 41, and they are provided with aligned apertures 50, for the reception of the shaft 45. This shaft is held against longitudinal movement by a set screw 51, which is received in a threaded aperture formed in the overhanging portion of the bracket 41. The lower terminal of the composite link 46 is pivotally secured to a sheet-supporting platform 52 by a pin or shaft 53, which extends through an aperture formed in the lower

terminal of the link and in aligned apertures 55 (Figures 7, 8) formed in bearing ears 56, which extend downwardly from the sheet-supporting platform 52. An arm 57 extends rearwardly from the platform 52, and this arm is pivotally secured to the lower terminal of a link 58, and the upper terminal of the link is pivotally secured to the bracket 41, as indicated at 60. By this arrangement, the sheet-supporting platform 52 is suspended for swinging movement from the bracket 41 by the suspension links 46 and 58, for a purpose to be hereinafter explained.

The body portion 47 of the composite link 46 is provided with an inclined cylindrical recess 23a, for the reception of a shaft 25, which is secured to the body 47 by a pin 26, or other suitable securing device. This shaft is similar in construction and arrangement to the shaft which supports the stationary sheet-guide roller 36, and it also supports a sheet-guide roller 36a of identical construction and arrangement, as the roller 36, and in the manner hereinbefore disclosed.

The bracket 41 is provided with an elongated slot 61, which slidably receives a bolt 62 having a flat head 63 and a conventional securing nut 65. The flat head 63 is held in vertical disposition by a rectangular projection 66, which is received within the slot 61 and interferes therewith to prevent rotation of the head 63. The head 63 is provided with a recess 67 for the sliding reception of a rod 68, which has a head 70, which is pivotally secured to the furcations of the composite link 46, by a pin or shaft 71. A helical compression spring 72 is supported by the rod 63, and the opposed terminals of this spring engage the heads 63 and 70 to thereby bias the suspended platform 52 and yieldable sheet-guide roller 36a for movement away from the bracket 41 toward the fixed sheet-guide roller 36, and this outward movement of the platform 52 and roller 36a is limited by the engagement of a stop finger 75, extending from the body 47 of the lever 46, with an inclined stop surface 76 formed on the foot of the bracket 41.

The relation of the hereinbefore disclosed sheet registering mechanism to the printing cylinders of the machine is well understood by those skilled in the art, and is also disclosed in the aforementioned Eckhard patent. The sheet-guide rollers 36 and 36a are to engage each sheet as it is being fed to the printing cylinders during a short time interval, and then the rollers are to be moved from engagement with the sheet, in common with the disclosures of the aforementioned Eckhard patent. The mechanism for moving the rollers 36 and 36a from engagement with the feeding sheets, is disclosed in the said Eckhard patent, and a sufficient number of the components for producing this operation is disclosed in this application.

Collars 77 and 77a are secured to the slidable supports 14 and 15 by thumb screws 78, and each collar is connected to a bell crank lever 80 through an interposed link 81. Each bell crank 80 is pivotally supported, as indicated at 82, on a bracket 83 carried by the side members 12 and 12a of the machine frame. The levers 80 are rocked about their fulcrums 82 by rotatable cams 85, which are driven from any suitable rotatable component of the printing machine, as disclosed in the cited Eckhard patent. Bell cranks 86 are pivotally supported on studs 87, and each bell crank 86 is operably connected to the bell crank 80 through an interposed link 88. Each bell crank

is rocked about its fulcrum stud 87 by the rotation of the engaged cam 85.

By this arrangement, the supports 14 and 15 are reciprocated so that each sheet is momentarily engaged by the side guide rollers 36 and 36a as the sheet is travelling toward the printing cylinders. It is preferred that the movement of the side guide rollers 36 and 36a be so timed that they will engage the sheet before it reaches the printing cylinders, and disengage it immediately after it reaches the cylinders and is taken by the cylinder grippers. The operation of the guides are preferably so timed that the roller 36a engages the sheet slightly in advance of the roller 36. Both rollers are in engagement with the sheet for a short period when the sheet is accurately positioned as to side register. After the sheet is taken by the grippers on the cylinder, the support carrying the roller 36a recedes, and immediately thereafter the roller 36 is withdrawn, thus leaving the sheet entirely free and laterally positioned for accurate side register.

In this improved registering mechanism, the arcuate peripheral surfaces 37 of the inclined guide rollers 36 and 36a engage the upper surface of each sheet as it is traveling toward the cylinders and lightly presses the edge portions thereof against the sheet supports to thus restrain the margins of the sheet that engage the side guide flanges 38 of the rollers 36 and 36a. At the same time, the flanges 38 of the guide rollers 36 and 36a position the sheet in predetermined lateral relation to the cylinders to insure accurate side register, and inasmuch as the roller 36 is not yieldably mounted, the side register will be determined by the position of the flange 38 of this roller. The roller 36a and platform 52 are sensitively mounted for yielding swinging movement away from the roller 36, and this movement is aided by gravity and is permitted by the yieldable spring 72, which constantly biases the roller 36a and platform 52 under relatively light tension for movement toward the roller 36. The roller 36a and platform 52 are suspended in balance for swinging movement by the links 46 and 53, and since the spring 72 exerts very light tension against the link 46, the roller 36a and platform 52 are sensitively suspended so that they can yieldingly move in a direction away from the roller 36 responsive to the slightest pressure exerted against the flange 38. By this arrangement the roller 36a and platform 52 readily yield to accommodate a metal sheet of minimum thickness and to also accommodate sheets formed of relatively soft material, such as cardboard and the like. Furthermore, the inclined disposition of the axes about which the rollers 36 and 36a rotate permits the portions of the flanges 38 which engage the sheet to be disposed in perpendicular relation to the sheet, and to present an effective arcuate peripheral surface to the lateral edge of the sheet in the plane thereof which has a contact curvature of greater radius than the actual radius of the annular peripheral surface at the sheet-engaging point in a plane perpendicular to the axis of the roller. In Figure 9, for sake of illustration, the dotted lines indicate the peripheral surface in actual radius of the sheet-engaging portion of a side-guide roller which is rotatable about a hypothetical vertical axis, whereas the hatched segment depicts the effective arc of the peripheral surface of the same sheet-engaging portion of a roller of equal diameter but which rotates about an inclined or oblique axis which is disposed transversely of the

feed plane. The effective peripheral contour which is presented to the lateral edge of the sheet by the flanges 38 of the rollers 36 and 36a may be varied by changing the configuration of the flanges 38 of these rollers. If the surface of the flange 38 which is presented to the sheet is of convex configuration, as depicted in Figure 10, the effective curvature presented to the edge of the sheet will be of greater radius than if this edge of the flange were conical.

By presenting an effective curved peripheral surface of relatively great radius to the lateral edge of the sheet, the pressure exerted against the sheet by the roller will be distributed over a larger portion of the edge of the sheet, to thus avoid denting or turning the edge of the sheet by the roller surface. Furthermore, the longitudinally curved surface of the roller body and the sheet support so confines the margins of the sheet that its edges are held in engagement with the flanges 38 of the rollers 36 and 36a. With this arrangement, relatively thin metal sheets or relatively soft sheets, such as cardboard and the like, may be employed without danger of curling or otherwise mutilating the edge of the sheet.

In existing side-guide mechanism, stationary shields, or other guide members, are provided to engage the upper surface of the sheet to force the lateral portions of the sheet downwardly. These stationary members offer some resistance to the movement of the sheet towards the cylinders, but this has been overcome in applicants' present arrangement, because all guide surfaces which engage any portion of the sheet rotate so that these surfaces move in the direction of movement of the sheet, thus obviating resistance to such movement. The side register is determined by the position of the flange 38 of the roller 36, and the flange 38 of the roller 36a yieldingly moves in a direction toward or away from the roller 36 to accommodate sheets of varying width, and the platform 52 moves with the roller but remains in horizontal disposition throughout the amplitude of its movement.

When both sides of the sheets are to be printed, it is usually necessary that the printing on both sides be in register with each other. To provide for this, the side guides are made interchangeable. One side of the sheet would be printed with the side guides mounted as shown in the drawings, but when the sheets are turned over to be printed on the other side, the guides would be interchanged, the rail 17 and the parts which it carries being mounted on the support 14, while the rail 16 and the parts which it carries would be mounted on the support 15. The printing would thus be registered to the same edge of the sheet for both printings.

It will be understood that the invention herein disclosed may be embodied in other specific forms without departing from the spirit or essential attributes thereof, and it is therefore desired that the present embodiment be considered in all respects as illustrative and not restrictive.

Having thus described the invention, what is claimed as new and useful is:

1. In a registering mechanism for side guiding a sheet in a printing machine to laterally position this sheet for side register as it is supported on and moves along a feed plane towards printing position, a roller located in the path of movement of the sheet and freely rotatable about an axis which is obliquely and transversely disposed relative to the feed plane and

having a peripheral surface which engages the top surface of the sheet, and also having an annular flange provided with an annular peripheral surface which rotates concentrically about the roller axis and engages an edge of the supported sheet in substantially perpendicular relation to the feed plane to thereby determine the lateral position of the sheet on the said plane, the oblique and transverse disposition of the roller axis causing the annular peripheral surface to present an effective arc to the edge of the supported sheet in the plane thereof of greater radius than the actual radius of the same surface at the sheet-engaging point in a plane perpendicular to the roller axis.

2. In a registering mechanism for side guiding a sheet in a printing machine to laterally position the sheet for side register as it is supported on and moves along a feed plane towards printing position, a roller located in the path of movement of the sheet and freely rotatable about an axis which is obliquely and transversely disposed relative to the feed plane and having an axially-elongated peripheral surface which is longitudinally curved and of varying radii and engages the top surface of the sheet, and also having an annular flange provided with an annular peripheral surface which rotates concentrically about the roller axis and engages an edge of the supported sheet in substantially perpendicular relation to the feed plane to thereby determine the lateral position of the sheet on the said plane, the oblique disposition of the roller axis causing the annular peripheral surface to present an effective arc to the edge of the supported sheet in the plane thereof of greater radius than the actual radius of the same surface at the sheet-engaging point in a plane perpendicular to the roller axis.

3. In a registering mechanism for side guiding a sheet in a printing machine to laterally position the sheet for side register as it is supported on and moves along a feed plane towards printing position, a non-yieldable guide member located to engage a lateral edge of a sheet as it moves along the feed plane, a rotatably-supported roller, means for suspending the roller from an axis which is remote from the roller for sensitive swinging movement about the said axis towards and away from the guide member to engage the opposite edge of the sheet, and means for biasing the roller for yielding swinging movement towards the guide member to thereby force one edge of the sheet against the guide member to determine the lateral position of the sheet on the feed plane.

4. In a registering mechanism for side guiding a sheet in a printing machine to laterally position the sheet for side register as it is supported on and moves along a feed plane towards printing position, a rotatably-supported non-yieldable roller located to engage a lateral edge of the sheet as it moves along the feed plane, a second rotatably-supported roller, means for suspending the second roller from an axis which is remote from the second roller for sensitive swinging movement about the said axis towards and away from the non-yieldable roller to engage the opposite edge of the sheet, and means for biasing the second roller for yielding swinging movement towards the non-yieldable roller to thereby force one edge of the sheet against the non-yieldable roller to determine the lateral position of the sheet on the feed plane.

5. In a registering mechanism for side guiding

a sheet in a printing machine to laterally position the sheet for side register as it is supported on and moves along a feed plane towards printing position, a non-yieldable guide member located to engage a lateral edge of the sheet as it moves along the feed plane, a platform for supporting the opposite lateral edge of the sheet, a rotatably-supported roller, means for suspending the rotatably-supported and the platform from an

axis which is remote from the roller and platform for sensitive swinging movement about the said axis towards and away from the guide member to cause the said roller to engage the said opposite edge of the sheet, and means for biasing the roller and platform for yielding swinging movement towards the guide member to thereby force one edge of the sheet against the guide member to determine the lateral position of the sheet on the feed plane.

20. 6. In a registering mechanism for side guiding a sheet in a printing machine to laterally position the sheet for side register as it is supported on and moves along a feed plane towards printing position, a rotatably-supported non-yieldable

25. roller located to engage a lateral edge of the sheet as it moves along the feed plane, a platform for supporting the opposite lateral edge of the sheet, a second rotatably-supported roller, means for suspending the second roller and the platform

30. from an axis which is remote from the second roller and platform for sensitive swinging movement about the said axis towards and away from the non-yieldable roller to cause the second roller to engage the said opposite edge of the sheet, and

35. means for biasing the second roller and platform for yielding swinging movement towards the non-yieldable roller to determine the lateral position of the sheet on the feed plane.

7. In a registering mechanism for side guiding

40. a sheet in a printing machine to laterally position the sheet for side register as it is supported on and moves along a feed plane towards printing position, a non-yieldable guide member located to engage a lateral edge of the sheet as it moves

45. along the feed plane, a platform for supporting the opposite lateral edge of the sheet, a rotatably-supported roller, means for suspending the rotatably-supported roller and the platform from axes which are remote from the roller and plat-

50. form for sensitive swinging movement about the said axes towards and away from the guide member to cause the roller to engage the said opposite edge of the sheet and to maintain the platform in parallel relation to the feed plane, and means for

55. biasing the roller and platform for yielding swinging movement towards the guide member to thereby force one edge of the sheet against the guide member to determine the lateral position of the sheet on a feed plane.

60. 8. In a registering mechanism for side guiding a sheet in a printing machine to laterally position the sheet for side register as it is supported on and moves along a feed plane towards printing position, a rotatably-supported non-yieldable

65. roller located to engage a lateral edge of the sheet as it moves along the feed plane, a platform for supporting the opposite lateral edge of the sheet, a second rotatably-supported roller, means for suspending the second roller and the platform

70. from axes which are remote from the second roller and platform for sensitive swinging movement about the said axes towards and away from the non-yielding roller to cause the second roller to engage the said opposite edge of the sheet and

75. to also maintain the platform in parallel relation

to the feed plane, and means for biasing the second roller and platform for yielding swinging movement towards the non-yieldable roller to thereby force one edge of the sheet against the non-yieldable roller so that both rollers are rotated in the direction of movement of the sheet by frictional contact with the sheet and to determine the lateral position of the sheet on the feed plane.

9. In a registering mechanism for side guiding a sheet in a printing machine to laterally position the sheet for side register as it is supported on and moves along a feed plane towards printing position, a non-yieldable guide member located to engage a lateral edge of the sheet as it moves along the feed plane, a rotatably-supported roller, means for suspending the roller from an axis which is remote from the roller for sensitive swinging movement in directions responsive to and against gravity about the said axis towards and away from the guide member to engage the said opposite edge of the sheet, and means for yieldably biasing the roller against gravity in a direction towards the non-yieldable guide member to permit the roller to yieldingly gravitate against the said bias when engaged by the sheet to determine the lateral position of the sheet on the feed plane.

10. In a registering mechanism for side guiding a sheet in a printing machine to laterally position the sheet for side register as it is supported on

10 and moves along a feed plane towards printing position, a non-yieldable guide member located to engage a lateral edge of the sheet as it moves along the feed plane, a platform for supporting the opposite lateral edge of the sheet, a rotatably-supported roller, means for suspending the roller and the platform from an axis which is remote from the roller and platform for sensitive swinging movement in directions responsive to and against gravity about the said axis towards and away from the guide member to engage the said opposite edge of the sheet, and means for yieldably biasing the roller and platform against gravity in a direction towards the non-yielding guide member to permit the roller and platform to yieldingly gravitate against the said bias when engaged by the sheet to determine the lateral position of the sheet on the feed plane.
